CLAIM

The ornamental design for a gastrostomy device with obturator, as shown and described.

DESCRIPTION

FIG. 1 is an exploded perspective view of a gastrostomy device with obturator, showing my new design;

FIG. 2 is a right side elevational view thereof;

FIG. 3 is a left side elevational view thereof;

FIG. 4 is a bottom plan view thereof;

FIG. 5 is a top plan view thereof;

FIG. 6 is a front elevational view thereof, the rear elevational view being identical thereto; and,

FIG. 7 is a front elevational view of the obturator device inserted into the gastrostomy device.
